UNITED STATES PATENT OFFICE.

ALBERT E. SIMMONS, OF EUREKA, CALIFORNIA.

REFILL CARTRIDGE FOR LUBRICANT GUNS.

Application filed March 21, 1921. Serial No. 454,100.

To all whom it may concern:

Be it known that I, ALBERT E. SIMMONS, a citizen of the United States, and resident of Eureka, county of Humboldt, and State of California, have invented a new and useful Refill Cartridge for Lubricant Guns, of which the following is a specification.

My invention while relating in general to lubricant guns has reference more particularly to an improved means of introducing the lubricant into the cylinder of the gun where it may be acted upon by the piston and forced through the discharge spout in the customary manner. The salient feature of the invention resides in an arrangement whereby lubricants for grease guns may be conveniently vended in a package which is suitable for use in combination with the cylinder of the gun for conveniently effecting a transfer of the lubricant from the package to the gun cylinder.

In the accompanying drawing which illustrates the preferred manner of reducing the invention to practice, Figure 1 is a view in side elevation and partly in section of the package which contains the lubricant as it is sold to the trade in accordance with my invention; Figure (2) is a view in side elevation and partly in section of a lubricant gun; Figure (3) is a detail perspective view of the ring member, which is employed in connection with the package and Figure (4) is a longitudinal section of a portion of the cylinder of a lubricant gun and the package as cooperating therewith in effecting a transfer of the lubricant from the package into the gun.

Referring now to the drawings in detail (A) represents a lubricant gun, which may be of a more or less conventional construction and including a discharge spout (B) through which the lubricant is discharged by pressure exerted by a downward thrust of the piston (C) through the rod (D) and the hand-hold (E). The cylinder of the gun has a threaded cap closure (F) which may be removed to open the end of the cylinder and through which the rod (D) of the piston (C) is free to reciprocate.

As heretofore practiced, lubricant used for these guns is purchased on the market in various kinds of containers and considerable inconvenience is experienced in transferring the lubricant from the container into the gun. It requires not only time but it is extremely difficult to pack the lubricant in the

gun so that a complete charge may be made ready to be acted upon by the piston when pressure is exerted to force the lubricant through the discharge spout (B). 60

According to my invention, these and other disadvantages as experienced with these heretofore employed means have been entirely overcome and I have provided an extremely simple and convenient means 65 which may be relied upon as a practical solution of the problems involved. According to the preferred embodiment of my invention I propose to sell the lubricant to the trade in cylindrical shaped packages, preferably, but 70 not necessarily made of fiber or paper, such as the open ended tube (5). Each of the ends of the tube may be closed by a removable cap (6). These packages in reality become so called cartridges and the length of 75 the same may vary according to the amount of the lubricant to be contained therein, but their transverse dimensions must be more or less accurately determined according to the diameter of the grease gun, with which they 80 are to be used. For instance, grease guns are made of different diameter, consequently these cartridges will have to be made in different corresponding diameters, the reason for which will presently follow: 85

In practice when a refill of the lubricant gun is to be made, the cap (F) of the gun is unscrewed and taken off and the piston (C) will be carried thereby and leave the cylinder of the gun with an unobstructed open end. 90 One of the caps (6) preferably that cap which has associated with it the ring (7) is removed and the cartridge presented over the cylinder of the gun so that the same may telescope therewith, with the ring (7) maintained at the addition of the cylinder so that when a downward thrust is imposed on the cartridge to telescope the same with the cylinder, the ring (7) will cut the lubricant from the walls of the cartridge so that all 95 100 of the lubricant may be properly introduced or transferred into the gun cylinder. The ring (7) also performs a further function by providing a tight seal between the cylinder and the cartridge so that none of the lubricant will leak through on the outside of the cylinder. The ring (7) may be made in any desirable form; according to the present showing it is expansible.

I consider this arrangement to be a highly 110 desirable improvement over the old methods employed, especially as the same may be

manufactured at a comparatively modest cost which will not take away from the commercial possibilities.

I claim:

- 5 A refill for lubricant guns, including a cartridge made to contain a charge of lubricant for the gun, a removable cap closure for the cartridge, an expansion ring positioned in the cartridge in front of the lubri-

cant contained therein, said cartridge adapted to be telescoped over an open ended cylinder of the lubricant gun for transferring the lubricant in the cartridge into said cylinder and with said ring bearing against the open end of the cylinder substantially as and for the purpose described.

ALBERT E. SIMMONS.
